UNITED STATES PATENT OFFICE.

HENRY W. WILSON, OF JERSEY CITY, AND NELSON H. TALLMAN, OF WEST HOBOKEN, NEW JERSEY; SAID TALLMAN ASSIGNOR TO SAID WILSON.

AUTOMATIC TRAIN-STOP.

No. 910,838.

Specification of Letters Patent.

Patented Jan. 19, 1909.

Application filed October 12, 1907. Serial No. 397,045.

To all whom it may concern:

Be it known that we, HENRY W. WILSON, a citizen of the United States, and a resident of Jersey City, in the county of Hudson and State of New Jersey, and NELSON H. TALLMAN, a citizen of the United States, and a resident of West Hoboken, in the county of Hudson and State of New Jersey, have invented certain new and useful Improvements 10 in Automatic Train-Stops, of which the following is a specification.

In the control of trains under the well known block system of signals it has been found necessary to devise means whereby a 15 train may be stopped automatically should an engineer disregard a danger signal and running by the same enter a block already occupied by a preceding train. To this end various inventions have been brought forward of 20 varying degrees of usefulness, the greatest objection to the most successful of which has been the complicity of their construction and the ease of derangement thereof due to this fact and to the fact that they often depend 25 for operation upon an outside source of power, such as electricity, etc.

It is the purpose of our invention to provide an automatic train stop device of marked simplicity of construction and of 30 positive mechanical operation, dependent only upon the passage of a train over the track after having passed a set danger signal.

Our invention consists in the construction, combination, and mode of operation of parts 35 set forth in and falling within the scope of the claims hereto appended.

In the accompanying drawings like characters of reference denote like parts in all figures.

40 Figure 1 represents a side view in elevation of our invention as attached to a train and a railroad track; Fig. 2 represents a top view of the track portion of our improved safety device; Fig. 3 represents a plan view of our 45 invention as applied to the block system; Fig. 4 represents a sectional view in side elevation of the track box portion of our improved device; Fig. 5 represents a sectional view in end elevation on line 5—5 of Fig. 4, looking in the direction indicated by the arrow; Fig. 6 represents a sectional view in side elevation taken on a line vertically through the center of that portion of our improved device which is attached to the train; 55 Fig. 7 represents a sectional top view taken on line 7—7 of Fig. 6, looking in the direction of the arrow on said line; Fig. 8 represents a sectional top view taken on line 8—8 of Fig. 6, looking in the direction of the arrow on said line.

on line 7—7 of Fig. 6, looking in the direction of the arrow on said line; Fig. 8 represents a sectional top view taken on line 8—8 of Fig. 6, looking in the direction of the arrow on said line.

Referring now to the figures in detail for convenience in description, our invention may be divided into the track section A, signal section B, and train section C, and in connection with A we will first describe track 60 box A', Fig. 4.

Fig. 4, A' denotes the track box which is set longitudinally outside of and adjacent to the right hand rail (X Fig. 2) of the track and on the ends of the ties (y Fig. 2). Said box 70 A comprises an open top metal box 1, with unattached cover 2, the box 1 and cover 2 together being such a height that when they are set on ties y the top of cover 1 is level with the tops of rails X. On the inside of cover 2, 75 longitudinally along the center line thereof is secured a vertical plate 3, of a height equal to the depth of the box 1, and pivoted on rod 4; near the bottom of the box 1 at that end thereof which lies in the direction from which 80 trains approach. The opposite end of plate 3 is cut to form the curved edge 6 which rests upon a roller 16. Said roller 16 is carried by a rod 12 which travels in a curved slot 9 (Fig. 1), cut in the right hand wall (looking 85 in direction of train movement) of box 1, corresponding with curved edge 6; said rod 12 being carried by a vertical plate 10, slotted at the center to permit of roller 16 on rod 12, placed across that end of box 1 which lies in 90 the direction of train movement, and pivoted near the bottom thereof on rod 11. To the end of rod 12 which projects from the side of box 1 through said slot 9 is secured a chain 13, leading down around wheel 14, placed at 95 the opposite end, outside and near the bottom of box 1, and thence to connection with rod 17 (Fig. 2) for purposes hereafter to be described. To the outer side of plate 10 at the top thereof is attached bar 15 which will 100 be described hereafter.

Turning now to Fig. 2, attached to the ties y outside of and adjacent to the right hand rail X looking in direction of train movement, and further along the track in that direction 105 than track box A', are placed plates with uprights 19 and 23 respectively, the latter being nearer track box A'. Upright 19 is pivoted at its lower end and at its center is connected by toggle joint 19^a with a bar 20. Said bar 110

20 is connected in like manner at its other end at joint 21 with bar 22, which is of greater length and which in turn at its other end is pivotally connected with the upper end of 5 upright 23. Between its ends bar 22 is bent in such a manner that that section lies close to the vertical portion of rail X. Bars 20 and 22 are of such a length that when upright 19 stands in a vertical position, the oblique 10 angle formed by 20 and 22 at joint 21 projects above the top of rail X, and when upright 19 is swung down in direction of train movement said bars 20 and 22 will lie at joint 21 on a level with the top of rail X. From 15 the inside of the upper end of upright 19 projects an eye 29 to which is attached a rod 18 attached at its other end to rod 15, which, as has been described, is connected with plate 10 in such a manner that when upright 19 is 20 vertical said plate 10 will have swung, in a direction opposite to that of train movement, on its pivot 11 to a position practically parallel with the bottom of box 1. To the said other end of 18 is also attached rod 24, attached to the other end of which is chain 25 leading around wheel 26 and up through signal tower B to the inner end of danger signal arm 27 in such a manner that when upright 19 is vertical, said arm 27 will be in a vertical 30 position, or not in use. Thus it will be seen that when upright 19 is swung in direction of train movement on its pivot by the depressing of bars 20 and 22, at joint 21, the plate 10 (Fig. 4) in box 1 will assume a vertical position thereby raising one end of cover 2 and also danger signal arm 27, Fig. 1, will assume a horizontal position and show a danger signal to approaching trains in connection with safety signal arm 28, which is ordinarily 35 played alone. To eye 29 is also attached one end of a rod 17 which extends in a direction opposite to that of train movement to the beginning of the preceding block where its other end is attached to a chain 13 and its 40 connections (described in connection with Fig. 4) in such a manner that when upright 19, in any block, is swung in direction of train movement on its pivot, as has been described, the plate 3 (Fig. 4) in the preceding 45 block track box A' will be pulled from the vertical position, and the top 2 of said box lowered, while by means of rod 15 connected to plate 3 in said box the upright 19 of the said preceding block device will be swung to 50 a vertical position, thereby raising the joint 21 of rods 20 and 22 above the level of the rail X and through rod 18 etc. dropping danger signal arm 27 of said preceding block to a vertical position out of use.

55 The construction of Fig. 1 has already been described in that of Fig. 2.

In Fig. 5 is shown a sectional end view taken on line 5—5 of Fig. 4 and showing plate 10, roller 16, rod 12, etc.

60 Fig. 6 represents the train section C, or

that portion of our improved stop device which is attached to the train itself, being preferably fastened to the locomotive at the rear right hand side of the cow-catcher and thus adapted to travel over successive track 70 boxes A'. This section C comprises a plate 30, attached to the engine, secured to the lower end of which is cylinder 31, and to the upper end cylinder 32 spaced apart from 75 31 near the center of plate 30. Cylinder 31 is pierced by a bore permitting of movement therein of rod 33, which rod terminates at its lower end in a foot 35. A collar 34 near the upper end of rod 33 permits the rod to project far enough below the cylinder 31 to allow 80 the foot 35 to come in contact with and be pushed up by the cover 2 of a track box A' when any part of said cover is raised (best shown in Fig. 1) while another collar 34 near the lower end of rod 33 prevents said rod 85 from being pushed up through the cylinder 31 more than a required distance. Cylinder 32 is also pierced by a central bore terminating near the top in a cylindrical chamber 46 with a funnel-shaped bottom. Rod 36 90 moves in the bore in cylinder 32, extending below the same until in close proximity to the upper end of rod 33 when said rod is in its lowest position and terminating at its upper end in a head 37 fitting in the funnel-shaped 95 bottom of chamber 46. From the center of this head 37 and integral therewith projects a vertical rod 38 which is encircled by a spiral spring 39; spring 39 rests on the head 37 at the bottom and at the top bears against 100 a top member 47 which closes the chamber 46. Thus the spring 39 normally tends to keep the head 37 in its seat while a recess 40 in said top 47 over rod 38 permits said rod to move upward when the head 37 is forced out 105 of its seat by pressure on the lower end of the rod 36. Near the bottom of the cylinder 32 a pin 42 passes in and is pressed against the rod 36 by a spiral spring 43; in rod 36 just below the point where the pin 42 abuts said 110 rod, when in its normal or lowered position, is an annular recess 41 into which the said pin 42 is forced by the spring 43 when the rod 36 is pushed upwards, and thus said rod cannot again drop down to its normal position 115 until the pin 42 is pulled out of said recess 41. Through the wall of the cylinder 32 near the top slants a bore 44 opening into the funnel-shaped bottom of chamber 46, the head 37 of the rod 36 thus closing this bore 44 when 120 said head rests in its seat. The outer end of the bore 44 is connected by suitable means with the compressed air cylinders.

The mode of operation of train section C is as follows: The foot 35 being pressed up by the raised cover 2 of a track box A', the top of rod 33 strikes the bottom of rod 36 and in turn forces it up thereby removing head 37 from its seat and permitting compressed air to enter chamber 46 through the 125 130

uncovered end of 44; the head 37 being held in an elevated position by the forcing of pin 42 into recess 41, as described. From chamber 46 a pipe 45 and connections (not shown) 5 lead to the air brakes, and hence by the operations following the pressing up of foot 35, the air brakes are automatically set.

Referring now to Figs. 1 and 3 the mode of operation of our invention as a whole is as follows: X' represents the first block, Y the second block. At the first block when the system is first put into operation the upright 19 is in a vertical position and the lever rod 22 slants upward projecting above the top 15 and close to the rail X'; the cover 2 of track box A' being down. The safety signal arm 28 is normally set on all blocks, there being an aperture therein through which shows the danger signal 27 when the latter is set. As 20 the train enters the block X', the wheels press down 22, thus swinging 19 on its pivot; through this swinging of 19 and the rods 18 and 15 connected thereto, plate 10 is swung up in track box A', raising the cover 2 at one 25 end and through chain 13 and rod 17 swinging 19 of the next block to a vertical position and thus raising the corresponding rod 22 above the top of the rail in said next block. Also in block X' by means of 18, 24 and 25 30 the danger signal 27 is set. Thus should any succeeding train disregard the danger signal displayed in block X', the air brakes would be set through contact of 2 and the foot 35.

Returning to the first train, it having left 35 22 depressed, cover 2 up, and danger 27 set, traverses block X' and enters block Y, where as has been said, 22 has been raised; the train depresses 22 in Y thereby setting the danger signals in Y as has been described 40 in connection with X', and also through rod 17 which extends back to X', and chain 13, plate 10 in X' is lowered and thus cover 2; and through 15 and its connection danger signal 27 is lowered and rod 22 raised above 45 the rail. Hence the train sets the signal on the block which it enters, and leaves the preceding block clear, the same operation being repeated by all trains throughout the whole system.

Having thus described our invention, what we claim as new and desire to secure by Letters Patent is:—

1. In a train stop device automatic means for bringing to a stop a succeeding train 55 about to enter upon a section of track occupied by a preceding train, said stop means comprising a member adapted to be depressed by a wheel of said preceding train, and automatic means for rendering inoperative said stop means on said section as said preceding train leaves said section.

2. In a train stop device means connected with a section of track comprising a member adapted to be depressed by a first train on 60 said section, whereby means attached to a

second train are set in operation to prevent said second train from entering said section occupied by said first train.

3. In a train stop device means connected with a section of track and operated by a train entering said section, whereby a danger signal is set on said section, a pivoted member adapted to be elevated by said train and to contact with means secured to a succeeding train for halting said succeeding train before it enters said section already occupied by said first train.

4. In a train stop device, means operated by a first train for setting a danger signal at the end of a section of track, means for halting a second train about to enter said section when occupied by said first train, said means comprising track levers and a plate operated by said first train, said plate contacting with brake setting means on said second train, means operated by said first train upon entering a second section for dropping said signal on said first section, and means operated in like manner rendering inoperative said means for halting said second train entering said first section.

5. In a train stop device, means operated by a first train entering a section of track for setting, on said section, a danger signal and placing in an operative position means contacting with and operating brake setting means on a following train to prevent said following train from entering said section when occupied by said first train, and means operated by said first train upon leaving said section for returning to their unset positions said signal and said contacting means, and for placing in a position to be operated by said following train, upon entering said section, said means for setting said signal and said contacting means.

6. In a train stop device, a pivoted member adapted to be depressed by a train passing the point of its location, means operated by said pivoted member when depressed, for setting a signal arm at said point, means operated by said pivoted member when depressed, for elevating a plate member on the track at said point, and means attached to a train for setting the brakes on said train, comprising a foot member and connections, said foot member contacting with said plate member.

7. In a train stop device, a pivoted member adapted to be depressed by a train passing the point of its location, means operated by said pivoted member, when depressed, for setting a signal arm at said point, means operated by said pivoted member, when depressed, for elevating a plate member on the track at said point, brake-setting means attached to a train comprising and operated by a member contacting with said elevated plate member, and means operated by said pivoted member, when depressed, for lower- 120 125 130 135 140 145 150 155 160 165 170 175 180 185 190 195 200 205 210 215 220 ing a second elevated plate member at a preceding point on said track.

8. In a train stop device, a pivoted member adapted to be depressed by a train passing the point of its location, means for setting a signal at said point, means for elevating a plate member on the track at said point, means for lowering a second elevated plate member at a preceding point on said track, 10 and means for elevating a second pivoted member at a succeeding point on said track, all of said means being adapted to be operated by said depression of said first pivoted member.

15 9. In a train stop device, a pivoted member adapted to be depressed by a train passing the point of its location, means for setting a signal at said point, means for elevating a plate member on the track at said point, 20 means for lowering a second elevated plate member at a preceding point on said track, means for lowering a signal arm at said preceding point on said track, and means for elevating a second pivoted member at a succeeding 25 point on said track, all of said means being adapted to be operated by said depression of said first pivoted member.

10. In a train stop device, a pivoted member adapted to be depressed by a train passing the point of its location, means for setting a signal at said point, means for elevating a plate member on the track at said point, 30 means for lowering a second elevated plate member at a preceding point on said track, means for lowering a signal arm at said preceding point on said track, and means for elevating a second pivoted member at a succeeding 35 point on said track, all of said means being adapted to be operated by said depression of said first pivoted member.

40 11. In a train stop device, a pivoted member adapted to be depressed by a train passing the point of its location, means for setting a signal at said point, means for elevating a plate member on the track at said point, 45 means for lowering a second elevated plate member at a preceding point on said track, means for lowering a signal arm at said preceding point on said track, and means for elevating a second pivoted member at a succeeding 50 point on said track, all of said means being adapted to be operated by said depression of said first pivoted member.

ing a third pivoted member at a succeeding point on said track, all of said means being 55 adapted to be operated by said depression of said first pivoted member, and brake-setting means attached to a train, comprising and operated by a member contacting with one of said elevated plate members. 60

12. In a train stop device a plate member adapted to be elevated on a track at the end of a section of said track by a train entering said section, brake-setting means attached to a second train comprising a plurality of 65 cylinders, rods passing through said cylinders, a chamber in one of said cylinders, inlet and outlet passages connected with said chamber, a stopper member opening the connection (when elevated) between said passages, and 70 a foot member on one of said rod members and contacting with said elevated plate member, whereby said stopper member is elevated.

13. In a train stop device, a pivoted member adapted to be elevated upon the passage 75 of a train, a pivoted lever located in advance of said member, and connections between the member and the lever, said lever being adapted to be elevated upon the elevation of said member. 80

14. In a train stop device, a plurality of bars pivotally connected adapted to be depressed by a wheel of a train, a plate adapted to be elevated upon the depression of said bars, and brake setting means on a second 85 succeeding train adapted to be operated by said plate when elevated.

15. In a train stop device, a pivoted upright adapted to be operated upon the passage of a train, a signal, a plate member, a 90 second plate member, and connections between said upright and said signal and plate members respectively, said signal being adapted to be operated and said first plate member to be elevated and said second plate 95 member to be lowered upon the operation of said upright.

In testimony whereof we have hereunto signed our names in the presence of two subscribing witnesses.

HENRY W. WILSON.
NELSON H. TALLMAN.
